UNITED STATES PATENT OFFICE.

JOHN SHEWCHUK, OF HAMTON STATION, SASKATCHEWAN, CANADA, ASSIGNOR OF ONE-HALF TO HENRY KLETZKY, OF HAMTON STATION, CANADA.

AX.

1,318,612.

Specification of Letters Patent. Patented Oct. 14, 1919.

Application filed May 7, 1919. Serial No. 295,432.

To all whom it may concern:

Be it known that I, JOHN SHEWCHUK, a citizen of the Dominion of Canada, residing at Hamton Station, in the Province of Saskatchewan and Dominion of Canada, have invented certain new and useful Improvements in Axes, of which the following is a specification.

The primary object of the invention is to provide an ax having an extensible head whereby the cutting edge may be adjusted relatively of the helve or handle of the ax and a different form of cutting edge may be substituted when desired.

15 A further object of the invention is to provide an ax head adapted for mounting a cutting edge in adjustable positions relatively of the helve of the ax, whereby cuts of different lengths may be made by the ax 20 and a longer or shorter head provided in a single implement to suit different requirements of use.

With these general objects in view the invention consists of the novel combination 25 and arrangement of parts hereinafter fully described, illustrated in the accompanying drawing and then claimed.

In the drawing forming a part of this application like reference characters designate 30 corresponding parts throughout the several views, and

Figure 1 is a side elevation of my invention with the helve broken away,

Fig. 2 is an end view thereof with the 35 head partially broken away and

Fig. 3 is a transverse sectional view of the head taken upon line III—III of Fig. 1.

My invention comprises an ax broadly 40 consisting of a handle or helve 10 having a metal head 11 secured upon one end thereof in the usual manner with the end of the helve positioned through an opening 12 in the head and secured by an expanding wedge 13 driven into the helve. The head 45 11 consists of three parts, the enlarged end 14 attached to the helve 10 in the manner described, an interchangeable blade or cutting edge member 15 and a connecting extension member 16.

50 A V-shaped groove 17 in the outer edge of the enlarged attaching end 14 in a plane substantially parallel with the plane of the helve 10 is attached to receive a V-shaped rib 18 upon the adjacent end of the extension member 16. Engaging side shoulders

19 are provided at opposite sides of the rib 18 while securing screws 20 are extended through the joint formed by said rib and groove, the said screws being threaded into bushings 21 threaded into one side of the 60 member 14.

The blade 15 is provided with a V-shaped rib 22 which is adapted to seat in the groove 17 when desired, thereby positioning the cutting edge 23 of the member 15 in a position adjacent the helve 10 for cutting during the use of the ax. A V-shaped groove 24 in the outer end of the extension 16 is also adapted to receive the rib 22 of the blade member 15 when desired to position 70 the blade at a greater distance from the helve 10.

Screws 25 are provided for extending through the rib 22 and the adjacent portion of the extension 16 for securing the blade 75 member 15 upon said extension as illustrated in Fig. 1 of the drawing.

By this arrangement it will be seen that the blade member 15 may be secured upon the extension 16 to project either downwardly as illustrated in Fig. 1 of the drawing or in an opposite direction upward whichever desired, while the extension 16 may be eliminated and blade 15 secured to the attaching member of the head as may 85 be found desirable.

A separate form of blades or cutting members 15 may be provided for attachment to either the extension 16 or member 14 having for instance side cutters as well as 90 center cutters and also curved cutting edges besides straight cutting edges as herein illustrated.

The invention possesses great simplicity and provides a head having great strength 95 and adaptable for many different uses for which an ax is capable.

What I claim as new is:—

1. An ax comprising a helve with a head member secured to the end thereof, an extension member detachably secured to the head member, and a cutting member detachably secured to said extension member. 100

2. An ax head comprising an attaching portion, an extension member removably secured to one end of the attaching portion and a blade member interchangeable with said extension adapted for removable attachment to the extension member or said attaching portion at will. 105

3. An ax head comprising an attaching portion having a longitudinal groove in one end, an extension member having a projecting rib removably secured in the said groove, and having a longitudinal V-shaped groove in its free edge and a cutting edge member having a rib adapted to be removably secured in the groove of said extension: 5
4. An ax comprising a helve, a head having an attaching portion secured to said helve and provided with a V-shaped groove in its free edge in a plane substantially parallel to said helve, an extension having a V-shaped rib adapted for seating in said groove, securing means between said rib, the said extension having a V-shaped groove in its outer edge parallel with said rib and a cutting member having a V-shaped rib re- 10
- movably secured in the groove of said extension with its cutting edge in a plane substantially parallel with the said grooves. 20
5. An ax handle comprising an attaching portion having a V-shaped groove in one edge thereof with shoulders at opposite sides of the groove, interchangeable extension and blade members each having a longitudinal V-shaped rib adapted for selectively positioning in said groove of the attaching member and securing means carried by the attaching member spanning the groove 25 thereof adapted for engaging the V-shaped portion of the coöperating member when positioned therein. 30

In testimony whereof I affix my signature.

JOHN SHEWCHUK.
